UNITED STATES PATENT OFFICE.

SILAS DIXON AND ALBERT S. BALDRIDGE, OF OKLAHOMA, OKLAHOMA.

WEATHER STRIP.

Application filed July 16, 1918. Serial No. 245,240.

To all whom it may concern:

Be it known that SILAS DIXON and ALBERT S. BALDRIDGE, citizens of the United States, residing at Oklahoma city, in the county of Oklahoma and State of Oklahoma, have invented certain new and useful Improvements in Weather Strips, of which the following is a specification.

Our invention relates to a new and improved weather-proofing medium for doors and windows or other parts of buildings and the general aims are to provide a novel construction of weatherstrip capable of flexing from approximately four or more points in order to readily yield without undue strain on the entire strip; a strip having a face to always lie flat while engaging the desired surface and one possessing the general features of construction and advantages of the embodiment illustrated in the accompanying drawings with relation to the specification hereinafter following.

In the drawings, Figure 1 is a vertical sectional view through a window illustrating the use of our improvements and Figure 2 is a fragmentary perspective view of the weather strip.

In Figure 1, a window is illustrated having usual sliding sashes 24 and 25 mounted in a casement 26. The weatherstrip has walls 36 and 37 disposed at an angle, preferably a right angle, to each other and from which walls 38 and 39 extend at practically 45°, the latter wall having a flange 40 depending therefrom parallel with the wall 37. Four points of flexure are thus provided between the walls and flange. This weatherstrip is preferably used to close the space intermediate the inclined facing walls of

the top strip and bottom strip of the lower 40 and upper sashes respectively, being fastened in place by nails, screws or the like 45 passing through the wall 36, as at 41. Also this form is preferably used to close the space above sill 27 between the window sash 45 and the inner sill 42 and the space between the upper sash and a cross strip 43. With these forms, wall 38 along its free edge rests on a supporting surface while wall 37 and flange 40 respectively engage opposed surfaces between which they are disposed. The fastening elements 41 are used in each of the instances of the employment of the weatherstrip of Figure 2 in this figure. The strip is preferably made from flexible metal in a 55 single strip.

As merely the preferred embodiment is set forth, it is understood that changes within the scope and spirit of the invention may be resorted to.

We claim:

A weather strip of flexible metal consisting of a first and a second wall, said walls being at substantially a right angle to each other, substantially parallel walls inclined 65 with respect to and extending from the side edges of said walls, and a flange extending outwardly from one of said parallel walls in a plane substantially parallel to the first wall and intersecting the second wall. 70

In testimony whereof we affix our signatures in the presence of two witnesses.

SILAS DIXON.

ALBERT S. BALDRIDGE.

Witnesses:

GRACE WITT,
M. L. SPEELER.
